UNITED STATES PATENT OFFICE.

ARTHUR G. HUNTLEY, OF TOSTON, MONTANA.

DESIGN FOR A SHARPENING-TOOL.

SPECIFICATION forming part of Design No. 28,895, dated June 21, 1898.

Application filed May 18, 1898. Serial No. 681,071. Term of patent 7 years.

To all whom it may concern:

Be it known that I, ARTHUR G. HUNTLEY, a citizen of the United States, residing at Toston, in the county of Broadwater and State of Montana, have invented and produced a certain new and original Design for Sharpening-Tools; and I do declare the following to be a full, clear, and exact description of the invention, such as will enable others skilled in the art to which it appertains to make and use the same.

The invention relates to a new and original design for sharpening-tools; and it consists in a tool of the shape shown in the accompanying drawings, in which—

Figure 1 is a perspective view, and Fig. 2 is a cross-section.

The leading feature of the design consists of the longitudinal body portion, the sides of which diverge from the lower edge to points ²⁰ *a* and *b* and terminate in a rounded back *c*. *d* denotes the loop-shaped handle, that extends from the end of the tool.

What I claim is—

The design for a sharpening-tool as herein ²⁵ shown and described.

In testimony whereof I have hereunto set my hand in presence of two subscribing witnesses.

ARTHUR G. HUNTLEY.

Witnesses:

J. B. JOHNSTON,
A. I. REEVES.
